UNITED STATES PATENT OFFICE

171,202

COFFEE MAKER

Maurice H. Graham, John N. Polivka, John K. Hamilton, and Ronald Gage Davis, Minneapolis, Minn., assignors to Jet-O-Mat, Inc., a corporation of Minnesota

Application July 21, 1953, Serial No. 26,067

Term of patent 14 years

(Cl. D44—26)

To all whom it may concern:

Be it known that we, Maurice H. Graham, John N. Polivka, John K. Hamilton, and Ronald Gage Davis, have invented a new, original, and ornamental Design for Coffee Maker, of which the following is a specification, reference being had to the accompanying drawing, forming a part hereof.

Fig. 1 is a side elevational view of a coffee maker, showing our new design;

Fig. 2 is a rear elevational view thereof;

Fig. 3 is a top plan view thereof; and

Fig. 4 is a bottom plan view thereof.

We claim:

The ornamental design for a coffee maker, as shown.

MAURICE H. GRAHAM.
JOHN N. POLIVKA.
JOHN K. HAMILTON.
RONALD GAGE DAVIS.
